UNITED STATES PATENT OFFICE.

HALVAR HALVARSSON, OF BJALVERUD, SWEDEN.

AUTOMATIC CATTLE-FEEDING MECHANISM.

Application filed April 17, 1926. Serial No. 102,771.

This invention relates to improvements in automatic cattle feeding mechanism and its object is to provide such mechanism for installation in stables, barns and cattle houses whereby the cattle confined in the several stalls may be fed automatically thereby saving time and labor of one or more attendants ordinarily assigned to this work. Simplicity in construction, efficiency in operation and durability are objects of the invention.

With the foregoing and other objects in view the invention consists in the combination and arrangement of parts to be herein-after fully described, pointed out in the appended claims and illustrated in the accompanying drawings which form a part of this application and in which—

Fig. 1 is a front view of one embodiment of the present invention, the support elements being partly broken away.

Fig. 2 is an enlarged fragmentary sectional view of the control mechanism for the feed delivery mechanism.

Fig. 3 is a side view of Fig. 2, enlarged.

Fig. 4 is an enlarged fragmentary view of Fig. 1.

Fig. 5 is a cross sectional view taken on line 5—5 of Fig. 4.

Fig. 6 is a top plan view of Fig. 5.

Like reference characters denote corresponding parts throughout the several views.

The invention comprises a plurality of invertible feed containers normally supported in upright position in a stable, one container in each stall, by a pair of connected slide bars operable simultaneously in opposite directions by an actuating lever upon release of the same by a time latch, this release being effected automatically at a predetermined hour of the day.

The reference numeral 1 denotes a post or support of any preferred type, a plurality of said supports being provided in spaced relation throughout the stable, one of said supports at one end of the stable pivotally supporting a lever 2 upon the fulcrum 3 and all of the remaining supports 1 pivotally supporting links 4 upon pins 5, each of said links and said lever being pivotally connected to the top and bottom slide bars 6, 7 which are thus slidably associated with the several supports 1.

In each stall in the stable a pair of spaced uprights 8, 9 are provided in advance of the slide bars 6, 7 and are connected by a bar 10 upon which an invertible feed container

11 is pivotally supported, said feed container being substantially V-shaped with the larger end open, the support bars 10 passing through the contracted closed ends so that unless supported in upright position with the open ends uppermost said feed containers will gravitate into inverted position which position is denoted in Fig. 5 by the dotted lines. The said feed containers are disposed well above the usual feed trough (not shown) common to all stables so that in inverted position the larger ends of said containers will swing down and immediately above said trough to discharge thereinto the contents of the containers.

The mouth of each feed container, comprising the larger end thereof, is contracted slightly thus forming a short side 12 which, in the upright position of the container, is disposed adjacent the slide bars 6, 7 and spring arms 13, 14 secured at their outer ends to the sides of said containers extend inwardly toward the slide bars, the free or inner ends of said spring arms being curved toward each other and formed with elongated slots 15, the arm 13 of each container being disposed directly opposite the slide bar 6 and the arm 14 thereof directly opposite the slide bar 7 in the upright position of the container.

The top slide bar 6 is provided in each stall with an angular latch finger 16 the free end thereof being spaced outwardly from the bar for removable insertion in the elongated slot 15 of the spring arm 13 and the slide bar 7 being provided with a similar latch finger 17 for similar disposal in the slot 15 of the spring arm 14, said latch fingers having their free ends extending in opposite directions. The distance between the members of any pair of latch fingers, located in each stall, is such that when the feed container is in upright position and the links 4 in vertical position said latch fingers will engage with the slotted portions of the spring arms and maintain the feed containers in said position.

Referring again to the lever 2 the forward or pointed end 18 thereof is supported normally upon the bell-crank-lever 19 fulcrumed in a slotted portion 20 of a housing 21 supported upon legs 22, said lever end 18 also being engaged by one end of a pressure spring 23 carried by a support 24 whereby said lever is yieldingly moved into the position shown dotted in Fig. 2 into contact

with the stop pin 24. The inner end of the said bell-crank-lever is normally supported upon the threaded end of the alarm shaft 25 of the clock 26 disposed in the said housing 21, said housing being provided with the hinged door 27 and with the transparent wall 28 through which the face of the said clock may be observed.

The said bell-crank-lever is connected by 10 a wire rod 29 to a flat spring 30 secured at one end to the floor of the housing. In operation the alarm clock is set for a certain hour as usual. At that time the shaft 25 will rotate thus moving the bell-crank-lever 15 19 laterally upon its fulcrum until it passes out of engagement with said shaft 25 when the spring 30 and rod 29 will move it inwardly and downwardly out of the path of the end 18 of the lever 2 permitting the 20 spring 23 to drop said lever 2 into the position shown dotted in Fig. 2. This operation will cause the slide bars 6, 7 to move in relatively opposite directions disengaging the several latch fingers 16, 17 from the 25 spring arms 13, 14 when the feed containers will gravitate into inverted position emptying their contents into the feed trough.

Before the next automatic feeding the lever 2 must be re-set manually. This operation will cause the slide bars 6, 7 to move the members of each pair of latch fingers 16, 17 toward each other. An attendant may now enter each stall and re-position the feed containers, the inwardly curved spring 35 arms 13, 14 riding against the latch fingers will cause the same to seat in the perforations 15 and the mechanism is set for the next operation.

What is claimed is:—

- 40 1. In automatic feeding mechanism, a pair of connected elements slideable in opposite directions, time controlled actuating mechanism for said elements, a plurality of invertible gravity actuated feed containers, and means releasably connecting said containers whereby they are held in upright position against the force of gravity in the normal position of said elements and automatically released when the normal position of said elements is disturbed.
- 45 2. In automatic feeding mechanism, a pair of spaced connected bars slideable in opposite directions, time controlled actuating mechanism for said bars, a plurality of invertible gravity actuated feed containers, slotted spring arms for said containers, and spaced latch fingers carried by said bars for supporting engagement with said spring arms

when said bars are in normal position and for disengagement with said spring arms 60 when said bars are in abnormal position.

3. In automatic feeding mechanism, a pair of spaced connected bars slideable in opposite directions simultaneously, time controlled actuated mechanism for said bars, a plurality 65 of invertible gravity actuated feed containers, a pair of slotted spring arms for each container, one spring arm of each container being disposed directly opposite one member of each pair of bars, said spring arms 70 being curved inwardly at their free ends, and a latch finger carried by each of said bars for supporting engagement with one of said slotted spring arms in the normal position of said bars and containers and for 75 disengagement therewith in the abnormal position of said members.

4. In automatic feeding mechanism, a pair of connected elements slideable in opposite 80 directions, time controlled actuating mechanism for said elements, said actuating mechanism comprising a spring-pressed lever, an alarm clock and a bell-crank-lever connecting said elements until rendered inoperative through the predetermined operation of said 85 alarm clock; a plurality of invertible gravity actuated feed containers, and means releasably connecting said containers and said connected elements whereby said containers are retained in upright position against the action of gravity in the normal position of 90 said elements and automatically released when said normal position is disturbed.

5. In automatic feeding mechanism, a pair of spaced connected bars slideable in opposite 95 directions simultaneously, time controlled actuating mechanism for said bars, a plurality of V-shaped invertible gravity actuated feed containers, the large open end of each container having one contracted side, a pair of 100 slotted terminally curved spring arms for each container extending beyond the contracted side thereof, one spring arm of each container being disposed directly opposite one member of each pair of bars in the normal position of said members, latch fingers carried by said bars for supporting engagement with the slotted portions of said 105 spring arms in the normal position of said bars and containers and for disengagement 110 therewith when said normal position is disturbed.

In testimony that I claim the foregoing as my own I have hereto affixed my signature.

HALVAR HALVARSSON.
